UNITED STATES PATENT OFFICE.

NICHOLAS P. CLARK, OF LINCOLN, RHODE ISLAND, AND HENRIE D. STONE, OF BOSTON, MASSACHUSETTS, ASSIGNEES TO EDWARD B. SEAVER, OF BOSTON, MASSACHUSETTS.

SOLE-LAYING MACHINE.

SPECIFICATION forming part of Letters Patent No. 368,131, dated August 9, 1887.

Application filed June 27, 1887. Serial No. 242,634. (No model.)

To all whom it may concern:

Be it known that we, NICHOLAS P. CLARK and HENRIE D. STONE, residents, respectively, of Lincoln, in the county of Providence and 5 State of Rhode Island, and of Boston, in the county of Suffolk and State of Massachusetts, have invented certain new and useful Improvements in Sole-Laying Machines, of which the following is a specification.

10 This invention relates to machines for pressing cement-coated soles of boots or shoes against lasted uppers, and for holding the soles in close contact with the uppers while the cement is setting or hardening; and it consists 15 in the several improvements which we will now proceed to describe and claim.

Of the accompanying drawings, forming a part of this specification, Figure 1 represents a front elevation of our improved machine; 20 Fig. 2 represents a vertical section on line *xx*, Fig. 1. Fig. 3 represents a bottom view, hereinafter referred to. Figs. 4, 5, 6, and 7 represent detail sectional views, hereinafter described.

25 The same letters of reference indicate the same parts in all the figures.

In the drawings, the supporting-frame is composed of a base, *a*, vertical uprights *b*, *b*, attached to the base, and a jack-supporting 30 head, *c*, attached to said uprights. Fitted to move between guides formed in the base *a* is a plunger or slide, *d*, having on its enlarged upper end a hemispherical boss, *e*.

f represents a metal bed or plate having a 35 flat upper surface, and provided on its under side with a socket, *g*, formed to fit the boss *e* and move in any direction thereon, the socket being of less depth than the height of the boss, so that when the bed *f* is in a horizontal position space is afforded for the downward movement of any portion of the socket on the boss. 40 The sole pressing and molding pad *h*, of rubber or other yielding material, is attached to the bed *f*, and is permitted by the boss and socket 45 to tip in any desired direction, either longitudinally or laterally, and thus conform to any differences between the inclination or form of the bottoms of different lasts.

The jack which supports the last and the

upper thereon is composed of two standards, 50 *i*, *i*, constructed the one to support the heel and the other the toe portion of the last. Said standards are adapted to slide on horizontal guides on the head *c*, and are provided with studs *j*, *j*, which enter cam-shaped slots *k*, *k* in 55 a disk, *l*, Fig. 3, which is affixed to a vertical rod, *m*, journaled in a bearing in the head *c*. The upper end of said rod is provided above the head *c* with a handle or wheel, *n*, whereby it and the disk *l* may be rotated. The rotation 60 of the disk causes the cam-shaped slots *k*, *k* to move the standards simultaneously toward or from each other.

The plunger or slide *d*, supporting the pad *h* and its universally-tipping bed, may be raised 65 to press the sole against the lasted upper by any suitable means, and the pressure may be effected partly by the upward movement of the pad and partly by the downward movement of the jack, as in other sole-laying machines now in use, or wholly by the upward movement of the pad. We have shown in the present case an organization whereby the pressure is entirely effected by the upward movement of the pad.

o represents a lever, which is pivoted at *p* to the base *a*, and at *q* to the slide or plunger *d*. The outer end of said lever is connected with a foot-lever, *r*, which is pivoted at *s* to the base *a*. We prefer to employ a stout spiral spring, *t*, as the means of connecting the lever *o* to the foot-lever *r*, for a purpose hereinafter specified, although, aside from such purpose, an ordinary connecting-rod may be substituted for the spring. The depression 85 of the foot-lever *r* causes the elevation of the slide or plunger *d* and pad *h*, and partially presses the sole on the pad against the lasted upper, the pressure thus obtained being comparatively light.

u represents a piston or standard, which is fitted to slide in a socket formed for it in the plunger or slide *d*.

v represents a locking-cam, which is pivoted to the plunger *d*, and is formed to permit the upward movement of the plunger upon the standard *u* by the foot-lever *r*, as above described, but binds upon the standard and locks

the plunger *d* to it when the standard is raised, so that while the depression of the foot-lever *r* raises the plunger independently of the standard the raising of the standard by the power-driven devices, hereinafter described, causes the plunger to also rise. The lower end of the standard *u* is formed to bear on an eccentric, *w*, on a power-driven shaft, *a'*. The elevation of the eccentric by the rotation of the shaft *a'* raises the standard *u* and plunger *d*, and imparts the full and final pressure to the sole interposed between the pad and lasted upper.

The standard and plunger are locked in the position to which they are thus raised by a locking-cam, *b'*, pivoted to the base *a*, and arranged to bear on the standard and prevent its downward movement without opposing its upward movement, said cam being held in contact with the standard by a spring, *c*, acting on a lever, *d'*, attached to said cam.

We provide suitable means for automatically stopping the rotation of the shaft after each complete rotation—that is, when the eccentric, after raising the standard *u* and plunger *d*, has descended to its lowest position—and said means will be presently described.

It will be seen from the foregoing that when the operator has placed a sole on the pad *h* he raises the slide or plunger *d*, with the pad, by depressing the foot-lever *r*, thus bringing the sole to a bearing on the lasted upper. The downward movement of the foot-lever is continued until said lever strikes a lever, *e'*, which is pivoted at *f'* to the base *a* and is rigidly attached to another lever, *g'*, which normally stands in position to arrest a short arm, *h'*, pertaining to the clutch shown in Letters Patent to B. F. Young, dated November 2, 1875, No. 169,394. The engagement of the lever *g'* with the arm *h'* holds the shaft *a'* out of engagement with its driving-pulley, while the depression of said lever *g'* releases the short arm *h'* and engages the driving-pulley with the shaft, as described in said Letters Patent. It will be observed, therefore, that the depression of the foot-lever *r* first raises the plunger *d* and pad *h* and then starts the driving-shaft, which raises the eccentric, and with it the standard *u* and plunger *d*, and gives the full pressure to the sole, the standard and plunger being automatically detained in their raised position by the cam *b'*. The operator removes his foot from the foot-lever *r* before the shaft has completed a rotation, so that the lever *g'* is released and allowed to assume its normal position in season to arrest the arm *h'* and disconnect the shaft *a'* from the driving-pulley when the eccentric has reached the lowest point of its rotation. After the pressure has been applied to the sole and upper a sufficient length of time the operator turns the cam *b'* by the lever *d'* sufficiently to release the standard *u*, whereupon the standard, plunger, and pad fall until the standard bears on the depressed eccentric. The operator then, after removing the last with the upper and sole thereon from the jack and applying another last with an upper thereon to the

jack and placing another sole on the depressed pad, again depresses the foot-lever *r*, with the result already described.

The spiral spring *t*, connecting the lever *o* with the foot-lever *r*, enables said lever to be depressed after the plunger has been raised as high as it can be by foot-power, and thus operate the clutch-releasing device with certainty.

Gear *h*³ is loose on shaft *a'*, and is provided with an annular recess, *h*⁴, Fig. 4, adapted to receive a block, *h*², therein. Said block is connected with the short arm *h'*, by a pin, *h*⁷, which passes through collar *h*⁴ rigidly secured to shaft *a'*, Fig. 5. Short arm *h'* bears against one end of the lever *g'*, rigidly secured to one end of a short shaft, *f'*, journaled in frame *a*. On the other end of shaft *f'* is the lever *e'*, provided with a pin, *A*, passing under foot-lever *r*. (See Figs. 6 and 7.)

The position of the mechanism above described for operating the machine is in its normal or inoperative position. If, now, the operator depresses foot-lever *r* sufficiently to engage it with pin *A*, the operation depresses lever *e'*, and with it lever *g'*, until the end of said lever clears short arm *h'*, when, as gear-wheel *h*³ rotates to bring pocket *h*⁵ under block *h*², said block *h*² will turn on its stud *h*⁷, so that it will engage with said pocket, and by its connection with collar *h*⁴, through pin *h*⁷, will rotate shaft *a'*.

When, after foot-lever *r* has been depressed and the machine started, as above explained, the pressure of the operator's foot being removed, the devices resume the position shown in the drawings by the means of springs, (not shown;) but block *h*² will remain in its position in pocket *h*⁵, last described, until one revolution of shaft *a'* has been made, when short arm *h'* will come in contact with the end of lever *g'*, as shown in Fig. 7, striking the same with a yielding blow, this movement turning block *h*² into the annular groove *h*⁶ and stopping the machine, as shown and described in the hereinbefore-mentioned patent.

We claim—

1. In a sole-laying machine, the combination of a last-supporting jack, a sole-pressing pad formed to extend along the entire bottom of the sole, and a pad-support consisting of a single metal plate on which the entire length of the pad bears, a hemispherical boss, and a corresponding socket undersaid plate, whereby the latter is permitted to tip bodily in any direction, and a supporting device for said boss, as set forth.

2. In a sole-laying machine, the combination of a last-supporting jack, a sole-pressing pad, a slide or plunger supporting said pad, a foot-lever and devices co-operating therewith, whereby the slide or plunger may be partially elevated, a standard fitted to slide in a guide in said plunger, a power-driven shaft having an eccentric arranged to elevate the standard, a locking device whereby the plunger is automatically engaged with the standard by the upward movement of the latter,

and an automatic locking device whereby the standard and the plunger thereon are held at the point to which they are raised by the driving-shaft, as set forth.

5 3. In a sole-laying machine, the combination of a last-supporting jack, a sole-pressing pad supported by a ball-and-socket joint, as described, a slide or plunger supporting said ball and socket and pad, a foot-lever and devices co-operating therewith, whereby the slide or plunger may be partially elevated, a standard fitted to slide in a guide in said plunger, a power-driven shaft having an eccentric arranged to elevate the standard, a locking device whereby the plunger is automatically engaged with the standard by the upward movement of the latter, and an automatic locking device whereby the standard and the plunger thereon are held at the point to which they are raised by the driving-shaft, as set forth.

15 4. In a sole-laying machine, the combination of a last-supporting jack, a sole-pressing pad, a vertically-movable plunger supporting said pad, a foot-lever and devices, substantially as described, co-operating therewith,

whereby the plunger and pad may be raised by foot-power, a standard fitted to slide in said plunger, a power-driven shaft having an eccentric arranged to elevate the standard, a locking-cam whereby the plunger is locked to the standard when the latter is raised, a locking device which engages the standard and holds it at any point to which it may be raised, a normally-inoperative clutch adapted to connect the driving-shaft with a driving-pulley thereon, and a shifting device for said clutch arranged to be moved to make the clutch operative by the depression of the foot-lever, as set forth.

20 In testimony whereof we have signed our names to this specification, in the presence of two subscribing witnesses, this 21st day of June, A. D. 1887.
